UNITED STATES PATENT OFFICE

ARTHUR KLEINFELDT, OF NEW YORK, N. Y.

PERFORATED PAPER.

SPECIFICATION forming part of Letters Patent No. 669,203, dated March 5, 1901.

Application filed April 6, 1900. Serial No. 11,813. (No model.)

To all whom it may concern:

Be it known that I, ARTHUR KLEINFELDT, a citizen of the United States, residing in the city, county, and State of New York, have 5 invented certain new and useful Improvements in Perforated Paper, &c., of which the following is a specification, reference being had to the accompanying drawings, forming a part hereof.

This invention relates to the perforation (including partial cutting, scoring, &c.) of sheets of paper or other material to facilitate the tearing of the sheet along a predetermined line, whether for the purpose of opening a 15 package, envelop, wrapper, or other inclosure or for the purpose of removing a sheet or a portion of a sheet, as a coupon or check or sales-slip, or for any other analogous purpose. Perforation for such purposes has generally 20 consisted heretofore of a series of small round holes or of indentations or partial ruptures or of scores or cuts arranged in the line of the intended tearing or obliquely across such line. With great care it is generally 25 possible to tear along the intended line of such perforations, but without such care the actual line of tearing frequently runs off from the intended line because the tear or rupture is not always directed from one perforation 30 to the next.

It is the object of the present invention to so form the "perforations" (by which term it is intended to include not only actual removal of portions of the sheet of paper or 35 other material, but indentations, partial ruptures, cuts, scores, &c.) that the tear or rupture of the material between successive perforations shall be directed without fail from one into the next. In accordance with the 40 invention, therefore, the line of perforations is made up of a series of cuts or scores, each cut or score having one portion extended across the general line of the series, which is the intended line of tear, and another portion 45 extended from the first portion toward the next cut or score. Furthermore, an envelop to which the invention is applied may be provided with another feature of improvement to facilitate the opening of the envelop.

The invention will be more fully described hereinafter with reference to the accompanying drawings, in which—

Figure 1 is a view of an envelop formed with a series of cuts or scores following the line of one of the flaps. Fig. 2 is a detail 55 section on the plane indicated by the line 2 2 of Fig. 1. Fig. 3 is a detail view of a portion of the perforated flap shown in Fig. 1 with the tongue extended. Fig 4 is a view of an envelop formed with a double series of cuts 60 or scores near one edge. Fig. 5 is a view of a portion of a sheet of paper or material formed with two single series of cuts or scores, as in a check-book; and Fig. 6 is a view of a portion of a sheet of paper with a single series 65 of cuts or scores arranged to permit the paper to tear in either direction.

As represented in the drawings, the sheet of paper or other material to be torn is formed with a series of unbroken angular cuts or 70 scores along the intended line of tear, as from A to B in the several figures. Each cut or score, as represented in the drawings, consists of one portion, as *a*, which is extended across the general line of the series, preferably 75 in an oblique direction, and a second portion *b*, either straight or curved, extended from the first portion toward the next cut or score, preferably in the general line of the series, but directed inward somewhat toward 80 the side of the first portion of the next cut or score. The portions *a* and *b* being continuous form together a single unbroken angular cut or score. When the paper or other material is torn, starting at A, the second 85 portion of each cut or score will direct the tear or rupture from the first portion of the same cut or score to the first portion of the next cut or score, so that it is impossible for the line of tear to depart from the general 90 line of the series of cuts or scores. As represented at C in Figs. 1, 2, and 3, a tab or tongue may be formed between the ends of the two series of cuts or scores for convenience in starting the tear. This tab or tongue 95 C is defined by paralled incisions *c*, running to the edge of the flap of the envelop, and is extended beyond the line of the flap when the envelop-blank is cut, as clearly shown in Fig. 3. It may be scored; as at *c'*, and is then 100 folded with a double fold, as shown at *c''* in Figs. 1 and 2, so that its end coincides with the line of the flap. When the envelop is manufactured, the tab or tongue C is glued

down with the flap of which it forms a part, its end being covered by the end of the other flap, which is left unsealed until the envelop is used. The double fold c^2 forms a tab to be grasped between the thumb and finger for tearing the envelop open, and as it bends readily in either direction it does not afford a hold for the accidental opening of the envelop by engagement with another envelop or card.

It is obvious that the portion a of each cut or score might have at each end a second portion, turned one in one direction and the other in the other direction, as shown at b and b' in Fig. 6. In this modification, as in the form shown in Figs. 1, 3, 4, and 5, all portions of the cut or score are continuous, forming an unbroken angular cut or score differing from the cut or score shown in Figs. 1, 3, 4, and 5 only in having two angular portions instead of one. This arrangement permits the paper to be torn in either direction.

It will be understood that the form of cut shown in Fig. 6 may be used in place of the form shown in the other figures of the drawings in connection with the tongue or tab and is particularly useful where it is found desirable to use a tearing-flap having two or more angles at either of which the tearing may be started. It is also particularly adapted for use in the check-book shown in Fig. 5, as it enables the check to be torn either up or down.

It will be observed upon examination of Fig. 1 that the envelop or wrapper has a substantially triangular flap, with a series of cuts or scores substantially parallel with each side of the flap, the two series diverging from a common point. This arrangement not only permits the envelop or wrapper to be opened readily and quickly to the full width of the flap, so that the contents can be withdrawn without difficulty, but it leaves the envelop or wrapper otherwise intact, there being no strip to be torn out and to be dropped upon the floor or elsewhere.

I claim as my invention—

1. A sheet of paper or other material perforated with a series of unbroken angular cuts or scores, each cut or score having one portion extended across the general line of the series and another portion extended in the general direction of the series toward the side

of the first portion of the next cut or score, whereby in tearing the line of rupture is directed from one cut or score to another in succession throughout the series. 55

2. A sheet of paper or other material having a series of unbroken angular cuts or scores, each cut or score having one portion extended obliquely across the general line of the series and another portion extended from the end of the first portion in the general direction of the series toward the side of the first portion of the next cut or score. 60

3. A sheet of paper or other material having a double series of unbroken angular cuts or scores, each cut or score having one portion extended across the general line of the series and another portion extended in the general direction of the series toward the first portion of the next cut or score, and a tongue or tab at the starting end of said double series of cuts or scores. 70

4. A sheet of paper or other material having a double series of cuts or scores, each cut or score having one portion extended across the general line of the series and another portion extended in the general direction of the series toward the first portion of the next cut or score, and a tongue or tab at the starting end of said double series of cuts or scores, said tongue or tab having its end glued down and having an intermediate double fold. 75

5. A sheet of paper or other material perforated with a series of unbroken angular cuts or scores, each cut or score having one portion extended across the general line of the series and at each end of the first portion another portion extended in the general direction of the series toward the side of the next cut or score, whereby the paper may be torn in either direction. 85

6. An envelop or wrapper having two series of cuts or scores diverging from a common point, the cuts or scores of each series being oblique to the general direction of the series, and a starting tongue or tab at the point of divergence of the two series. 95

This specification signed and witnessed this 100
31st day of March, A. D. 1900.

ARTHUR KLEINFELDT.
